2 SHEETS—SHEET 2.

UNITED STATES PATENT OFFICE.

JOHN MORRIS LATIMER, OF PHILADELPHIA, PENNSYLVANIA, ASSIGNOR, BY MESNE ASSIGNMENTS, TO CONSOLIDATED FIRE ALARM COMPANY, A CORPORATION OF NEW YORK.

COMBINED TELEPHONE-EXCHANGE AND ALARM SYSTEM.

No. 804,441.

Specification of Letters Patent.

Patented Nov. 17, 1908.

Application filed April 21, 1900. Serial No. 13,762.

To all whom it may concern:

Be it known that I, JOHN MORRIS LATIMER, a citizen of the United States of America, and a resident of the city of Philadelphia, in the county of Philadelphia and the State of Pennsylvania, have invented certain new and useful Improvements in a Combined Telephone-Exchange and Alarm System, of which the following is a specification.

10 This invention is an improvement on the combined telephone exchange and fire-alarm system, which forms the subject of United States Letters Patent Number 647,307, issued to me April 10, 1900, for a combined telephone-exchange and fire-alarm system.

In this, as well as in the invention set forth in the above mentioned application, the object is to utilize existing telephone lines for the transmission of fire-alarms, burglar alarms, or other signals, from various points within a territory covered by a telephone-exchange system to a fire, police or other alarm-receiving headquarters, by means of suitable local transmitting apparatus and repeating apparatus connected to the telephone-lines, but so constructed that they will not interfere with the telephone-signaling or talking currents, or the sets of local telephone-apparatus at the various points. In other words, the leads of the telephone-subscribers' circuits, which come together in a telephone-exchange, are used for two distinct and independent classes of service. These are, first, an exchange-service, in which local telephone-subscribers signal to a telephone-exchange and obtain telephone-connections with one another; and, second, a service in which suitably arranged and connected sets of apparatus at various points are provided, with which signals can be transmitted over the leads of the telephone-subscribers' circuits, and these signals are received at a point which is separate and distinct from the telephone-exchange. This second service is by way of distinction termed an alarm-service.

The sets of apparatus for the alarm-service at the various points from which signals can be sent, are termed sets of local alarm-transmitting apparatus, and the apparatus at the point to which the signals are sent will be termed the alarm-receiving apparatus. These terms, however, are not intended to limit the claims to systems in which the signals are distinctly alarm-

signals, since the system is equally applicable to the transmission of signals for any purpose.

In the system as herein disclosed, neutral relays are placed in the leads of the telephone-circuits at the exchange to repeat the signals from the telephone-circuits to the circuits extending to the alarm-receiving headquarters. The telephone-lines are also utilized for transmitting answering signals to the local points from which the alarm-signals are transmitted, and to establish direct telephone connection between the points from which the alarm-signals are transmitted and the alarm-receiving headquarters.

The construction is such that these objects are attained without interfering with the ordinary telephone-exchange service over the lines.

The telephone-circuits radiate from a telephone-exchange to various sets of telephone-subscribers' apparatus, and these circuits are primarily constructed for the purpose of connecting the telephone-subscribers with the exchange. The sets of alarm-transmitting apparatus are connected to the lines of the telephone-circuits which are most conveniently reached; and the system is such as not to interrupt the telephone-exchange service, or be interrupted by the telephone-exchange service. The construction is also such that the telephone-subscriber's service is not interrupted at any time or disturbed, except at the actual instant of sending signals. The signals from the sets of local alarm-transmitting apparatus are received by alarm-repeating relays at the telephone-exchange. These relays are so constructed that they will respond to signals from the sets of local alarm-apparatus, but will not respond to the telephone-subscribers' signaling and talking currents.

The alarm-signal currents may or may not affect the telephone signal-receiving devices at the switchboard, but if they do, their special character will be easily recognized by the exchange-operators, and not be mistaken for telephone-subscribers' calls. The signals are automatically transmitted by the alarm-repeating relays in the telephone-circuits to the alarm-receiving headquarters, and their transmission is consequently independent of any attention from the exchange-operators, and, therefore, not subject to the danger of oversight or delay on their part,

as would be the case if they were required to repeat the signals. The construction also is such that it is immaterial whether or not the telephone-circuit is in use for conversation 5 and connected to another telephone-circuit at the exchange, when called upon for the transmission of alarm-signals. It is important to be independent of this condition, because, when the telephone circuit is 10 connected to another exchange by means of a trunk connection, the telephone-subscriber's clearing-out signal would, according to usual telephone practice, be cut out at the local exchange, and only be received in the exchange 15 at the long-distance point, in the event that the distant subscriber is the calling subscriber, and, therefore, if an alarm-signal depended for indication upon the local exchange, there would be no means, under 20 these conditions, of indicating it at the local exchange, and it would go to the distant exchange instead, which might be in another city.

In the accompanying two sheets of drawings, which form a part of this specification, Figure 1 is a diagram showing an alarm-system applied to a common-battery exchange in which the alarm-transmitting sets and the alarm headquarters are in communication through a duplex telephone-system. Fig. 2 is a diagram showing an outdoor police telegraph and telephone-system, an out-door public fire-alarm telegraph and telephone-system, and an indoor automatic or manual private alarm-service, all applied to a common-battery exchange, as in Fig. 1.

The system as shown in Fig. 1 will first be described:—The telephone-subscribers' sets 1, of which but one is shown, are connected 25 to a common-battery telephone-exchange by the battery-leads 2 and grounded leads 3, which form the telephone-subscribers' circuits and connect the subscribers' sets with the open-terminal spring-jacks 4 and the 30 grounded common-battery 5. The battery leads are connected through line-signal relays 6 to the live terminal of the common-battery, and the grounded leads are connected to the grounded terminal of the common-battery. The line-signal relays close 35 circuits through line-signal lamps 7. In front of the spring-jacks for each circuit are test rings 8, which are connected through an exchange cut-off relay 9 to the grounded terminal of the common-battery. The insertion of the usual exchange cord-circuit plug 40 in the jack of a telephone-subscriber's circuit, connects the test-ring with the live terminal of the battery, and with the cut-off 45 relay shifts the connections of the grounded lead of the telephone-subscribers' circuit to ground through a repeating-coil in the cord-circuit, and shifts the connections of the battery-lead of the telephone-subscriber's circuit 50 in the battery through another repeat-

ing-coil in the cord-circuit. In the cord circuit are placed signal-lamps, which light on the cessation of battery current. Such a cord circuit is illustrated in United States Letters Patent to H. M. Crane, No. 620,745, 70 dated March 7, 1899.

The alarm-system and the manner in which the telephone-circuits are utilized for the transmission of alarm-signals will now be described. At convenient points within 75 the territory covered by the exchange are sets of local alarm-transmitting apparatus each consisting either of a signaling-wheel 10 and mechanism for operating it manually or otherwise, or a telegraph-key 11. Each 80 of these is connected to the battery lead of any telephone-subscriber's circuit, which may be conveniently near and effects connection between the lead and the ground. The telephone-circuits to which such connections 85 are made have, in both leads at the exchange, alarm-repeating relays 12, which are neutral relays, with the coils balanced in the two leads. All currents, which are used in signaling and telephoning between telephone- 90 subscribers and the telephone-exchange, course through both leads and both coils equally, but oppositely around the relay-core, thereby neutralizing each other, and, hence, do not affect the relay. But when a 95 contact is made by the alarm-transmitting apparatus between the battery-lead of the telephone-circuit and the ground, the common-battery current will flow through one coil only of the relay and it will attract its 100 armature. Each relay controls contacts 13, which are in multiple in an alarm-transmitting circuit 14. The closure of the contact at any relay, therefore, closes the alarm-transmitting circuit. With the system connected as illustrated, the sending of an 105 alarm-signal would cause a flashing of the line signal-lamp, which would be recognized by the exchange-operator as an alarm-signal, and not as a subscriber's call, and no attention would be paid to it by the exchange-operator, whose business is to answer subscribers' calls and connect telephone-subscribers. If, while such an alarm were coming in, the telephone-subscriber of the line 110 should take off his telephone-receiver, the 115 flashing signal-lamp would change to a continuous light, thereby indicating a subscriber's call, and the alarm-signals would cease to flash on the lamp, although they 120 would continue to operate the neutral relay, and be repeated thereby to the alarm-headquarters.

In series with each relay-contact is a coil of an automatic cut-out switch magnet 15 125 and a slow-acting cut-out switch 16 which is controlled by the cut-out switch magnet and opened when the magnet is fully energized. The core of each of these magnets, especially at the pole-pieces, is surrounded with copper 130

sleeves so that the magnet will magnetize slowly and will not attract its armature and open the alarm-transmitting circuit until after a short interval. The cut-out switch magnet is also made to respond slowly to current by providing it with two armatures so adjusted that the one controlling the contact will not be attracted to the core until the other has been attracted to the core, and has thereby strengthened the magnetic circuit. Between the closure of the alarm-transmitting circuit at the relay and the opening of this circuit by the cut-out switch there is sufficient time to send an impulse such as is requisite in sending a signal. Because of the construction above indicated, this cut-out switch operates whenever current comes into its coil and remains for a length of time, consequently in event of any current coming onto a line, which would operate its alarm-repeating relay, and remaining on, this cut-out switch magnet will operate and open that branch of the alarm-transmitting circuit which is through the relay-contact made by the alarm-repeating relay, so that signals received on other alarm-repeating relays can be repeated on this alarm-transmitting circuit. The purpose of this cut-out switch is, therefore, to prevent the complete disabling of the entire alarm-system through the individual disabling by the continuous grounding of, or the presence of a foreign current in, any one of the telephone-circuits which is utilized for transmitting alarm-signals. The cut-out magnet on operating and opening the alarm-transmitting circuit, effects the closure of a contact 17 of a circuit through its coils and the contact of the neutral relay. As long as the grounding of the line or foreign current continues on the line, the contact 13 remains closed, and the cut-out switch-magnet 15 remains energized, and the contact 17 remains closed, since there will be a circuit from the common battery through the cut-out switch-magnet, through the contact 13, and through the contact 17 to the other side of the common battery. It, therefore, remains energized as long as the relay remains energized, and prevents any permanent closure of the alarm-transmitting circuit at the relay. Upon the cessation of the current which rendered the individual alarm-relay inoperative, the cut-out magnet will release its armature and the alarm-transmitting circuit will be restored to control by the neutral relay in the circuit which was disabled.

The alarm-transmitting circuit 14 is wholly within the exchange and is preferably a normally open circuit. It is supplied from the common-battery and contains a relay 18 which controls a contact in a second transmitting circuit 19 extending to the relay 20 at the alarm-receiving headquarters.

In order to save wires, the telephone leads

21 between the headquarters and the exchange are used in parallel for the transmission of these signals by a duplex arrangement, which is non-interfering with the telephone circuit. Branches from both leads 79 at the headquarters are led through impedance coils 22' and joined to the lead of the circuit 19'. Branches from both leads at the exchange are led through impedance coils 22' and joined to the leads of the circuit 19. The circuit is from the common-battery through the contact of the relay 18 to the point of juncture of the branches from the telephone-leads at the exchange, thence in parallel over these branches and 30 the impedance coils in the exchange branches, the telephone leads, the branches from the telephone-leads and the impedance coils to the point of juncture at the headquarters, thence through the relay 20 and 85 telegraph-key 23 to ground, and back to the common battery, thus completing the circuit. The relay 20, on operating, closes a local circuit through a local battery 24, and an alarm-receiving apparatus consisting of a 90 register 25 and bell 26. The transmitter and primary coil of the telephone-set 27 at the headquarters is also in this circuit.

The leads from the receiver and secondary coil of the telephone-set are carried to repeating-coils 28 on the cores of the neutral relays in the telephone-subscribers' circuits at the exchange. These coils are all connected, so that current, which may be induced in any one of the coils, will also flow 95 in the others. As shown in the drawings, they are connected by placing them in series in the circuit of the telephone at the headquarters. As the neutral relays are balanced with respect to the subscribers' circuits, currents in the repeating-coils will not repeat to these circuits. They will, however, each repeat to circuits in parallel over each of the telephone-subscribers' leads which join through condensers 29 in circuits through 100 the receiver and secondary coils of each of the local alarm-telephone sets 30 which are placed in conjunction with the local alarm-transmitting sets. The connections with each pair of telephone-subscribers' leads is 105 through two impedance-coils 22. These coils are non-inductive to currents passing through them in parallel, but alternating currents will not pass through them in series. These coils are wound on an iron 110 core, which forms a closed ring, and the connections to the windings are such that if the course of the current be traced through one coil, thence through the point of connection of the two coils with the local alarm 115 telephone-set, and thence back through the other coil, the circuit through both coils will be around the core in the same direction as though the two coils formed one continuous spiral. An alternating current attempting 120

130

to flow through the coils in this way, will be opposed by the rise of magnetization in the core, and an inappreciable current will actually pass over the coils in series. Consequently, the branches from the telephone-subscriber's circuit and the branches from the telephone-circuit between the alarm-headquarters and the exchange, although they shunt these circuits, do not impair their efficiency in the transmission of talking currents. On the other hand, an alternating current to or from the local alarm telephone-set will divide equally between the two coils, and, passing around the core simultaneously in contrary direction, will be neutral in magnetizing effect on the core, and there can be no rise of magnetization in the core to oppose the passage of such currents. The circuits in parallel are carefully balanced, so that they will neutralize each other with respect to the telephone-subscriber's apparatus. The condensers in the branches of the telephone-subscriber's circuit prevent the closure of this circuit through them to continuous currents, and hence do not afford a closed circuit to the common-battery. The repeating-coils 28 are wound with two parallel wires, and after winding one wire is connected in series with the other to reduce the impedance. Each repeating coil may be of ordinary construction, but I prefer, and show, a bi-filament winding. Two wires are wound together, and the wires of two windings, when completed, are connected in series. There is then a condenser effect between the two coils, which reduces the self-induction of the coils.

The sets of local alarm-telephone apparatus are constantly connected through the neutral relays and repeating-coils with the telephone-set at the alarm-headquarters, and with each other, it being necessary only to remove the receivers from the hooks to place them in communication. As the local-battery circuit through the telephone-transmitter at the alarm-headquarters is closed when the bell is sounded, it follows that the sounding of the bell at the headquarters can be heard in any telephone of the sets of local alarm-apparatus, and a person, when sending an alarm, can, by first listening in the telephone, ascertain whether or not he will interfere with a user of the system between any other local alarm-apparatus and the headquarters. By continuing to listen while signaling, he can also ascertain whether or not his signals are properly sounded at the headquarters. The alarm-transmitting apparatus and the alarm-receiving apparatus in each set of local alarm-apparatus are in different circuits, although they may use the same leads, and are independently operating, except for their connection through the relays and circuits at the telephone-exchange and at the headquarters. The oper-

ator at the headquarters can acknowledge and answer the signals, either by telephone or by means of a telegraph-key. This key, when opened, sounds the bell at the headquarters, the sound of which is transmitted over the telephone circuits to the local alarm-apparatus.

The currents established under the several conditions of operations will now be traced.

When a subscriber desires connection with another subscriber through the exchange, he removes his telephone-receiver from the hook in the subscriber's set 1, the hook rises and establishes a connection between the leads 2 and 3 in the set. The current from the common battery 5 can then flow through the subscriber's line-signal relay 6, upper contact of the cut-out switch 9, telephone battery lead 2, coil of neutral relay 12, primary of subscriber's induction coil, hook, transmitter, grounded lead 3, coil of neutral relay 12, in contrary direction to other coil of this relay and thereby not affecting it, lower contact of cut-out switch 9 to ground side of the battery. This circuit energizes the line signal relay 6, and this relay closes a circuit from battery 5 through the lamp 7 which notifies the exchange operator that the subscriber desires telephone connection. Insertion of a plug by the exchange operator energizes the cut-off relay 9 thereby disconnecting the leads 2 and 3 from the battery 5 through the line signal relay, but the leads are at the same moment again connected to the battery through repeating coils in the cord circuit in the usual way.

The variations in the battery current in talking are of course insufficient to be manifested at any of the relays. They are in contrary directions through the coils of the neutral relay 12, and they do not affect this coil, the talking current will not pass through the branch across the leads 2 and 3 through the impedance coils 22, for since their course is the same in each coil, their inductions are opposed. Battery current will not pass this branch because of the condensers 29.

When an alarm is transmitted by closure either at the signaling wheel 10 or key 11, a circuit is established from the common battery through the line signal relay 6, one coil of neutral relay 12 thereby operating the relay, lead 2, signaling wheel 10 or key 11 to ground of the local alarm transmitting apparatus, thence through the ground at the exchange to the other side of the battery. If at the time this signal is transmitted, the line is in use by a subscriber, the circuit will be from the common battery through one of the repeating coils in the cord circuit, cord and plug to the left side of the spring-jack 4 which is connected to the telephone lead 2, through one coil of neutral relay 12 which is in telephone lead 2, ground at the local

alarm transmitting apparatus, thence through ground at the exchange to the other side of the battery. This current in so far as it flows over the lead 2 will be superimposed upon and in addition to the current already flowing over lead 2 to the telephone subscriber's set and returning normally through lead 3 to the battery. The current through the coil of the neutral relay 12 10 which is connected to the lead 2 will consequently exceed the current which is returning from the subscriber's set over lead 3 and through the other coil of the neutral relay. The coils will therefore be out of balance and the relay will be operated as before.

Operation of the neutral relay closes a circuit located entirely within the exchange. This circuit is from the common battery 5, 20 through the automatic cut-out magnet 15, contact of the neutral relay, a contact 16 which is opened when the automatic cut-out magnet has fully operated its armatures and relay coil 18 to the ground side of the battery. The operation of the relay 18 opens a circuit to the alarm receiving headquarters. This circuit is from the common battery over the lead 19, a contact on the back of the armature of the relay 18, through impedance 30 coils 22' in parallel over the telephone leads 21 between the alarm headquarters and the telephone exchange, through impedance coils 22" to the point of juncture at the headquarters, thence through the relay 20 and telephone key 23 to ground, and back to the common battery, thus completing the circuit which is opened when a signal is transmitted. The operation of the relay 20 closes a circuit at the alarm receiving headquarters which is 40 from a local battery 24 to the operating coil of a register 25, the operating coil of a bell 26, the primary coil and transmitter of the telephone set 27 to the other side of the local battery.

Conversation between a local alarm telephone set 30 and the telephone set 27 at the headquarters is over a circuit over the condensers 29 in parallel the impedance coils 22 in parallel the telephone subscriber's leads 2 and 3 in parallel, the coils of the neutral relay 12 in the same direction, from lead 2 through line-signal relay 6 and common battery to ground, and from lead 3 to the common battery ground at the exchange and return through the ground at the local alarm transmitting station. Then talking currents are repeated by induction upon the neutral relay coils 12 to repeating coils 28 in a circuit consisting of two leads between the exchange, 55 where the repeating coils are located and the telephone receiver and induction coil at the alarm receiving headquarters.

The several classes of circuits in use in the transmission of an alarm are open circuits 60 with the exception of the circuit between the

exchange and the alarm receiving headquarters. For such important service as the transmission of alarms, it is desirable that circuits which are between different parts of a city and therefore cannot be as carefully 70 protected as circuits wholly within instruments or buildings should be normally closed circuits in order that they may be constantly under battery test, as then any interruption would immediately become known and could 75 be more promptly repaired. But in utilizing telephone circuits this is not necessary since their frequent use for telephone purposes affords sufficient warning of any interruption. As the circuit between the exchange 80 and the alarm receiving headquarters is used for the transmission of all alarm signals it is of special importance that immediate warning should be given of any accident and this circuit is therefore preferably arranged as a 85 normally closed circuit.

The system as shown in Fig. 2 will now be described. This shows a common-battery telephone-exchange, as in Fig. 1, with five complete telephone-subscribers' sets and circuits connecting them with the exchange. The telephone-circuits are utilized for three classes of alarm-service, and the alarm-signals in each class are received in separate alarm-transmitting circuits at the exchange. 90 These three classes of service are as follows:—(a) An out-door public or municipal fire-alarm service for use by policemen, firemen and others, comprising sets of local fire-alarm apparatus each consisting of automatic or manually operated signaling-wheels 10^a a telegraph-key 11^a and a telephone-set 30^a for sending fire-alarm and special signaling to and affording direct telephone communication through relays 12^a and 18^a, telegraph circuits 14^a and 19^a and telephone circuits 21^a with the headquarters apparatus, comprising the relay 20^a, register 25^a, bell 26^a and telephone set 27^a; (b) an out-door public or municipal police service 100 comprising sets of local police signal apparatus, each consisting of a manually-operated signaling wheel 10^b, a telegraph-key 11^b, and a telephone-set 30^b for sending signals to and affording direct telephonic communication through relays 12^b and 18^b, telegraph circuits 14^b and 19^b and telephone circuit 21^b with the police headquarters' apparatus, comprising the relay 20^b, register 25^b, bell 26^b and telephone-set 27^b; (c) an in-door automatic or manual private alarm service for sending distinctive signals by means of a local alarm set with a signaling-wheel 10^c, through relays 12^c and 18^c, and through circuits 14^c and 19^c to a private fire, police or other alarm-receiving headquarters, comprising the relay 20^c, register 25^c, and bell 26^c.

The apparatus and circuits for the first two of the three foregoing classes of service are substantially identical in their arrange- 130

ment and operation, with the apparatus and circuits described in connection with Fig. 1, and the apparatus and circuits for the third class of circuits differs from the system of Fig. 1 chiefly in the omission of the telephone-sets. The sets of local fire-alarm apparatus differ from the sets of local police signaling-apparatus in that the former is provided with mechanism for rotating the signaling-wheel a number of times, and thereby repeating the signal, while the mechanism of the police signaling-apparatus imparts but one revolution to the signaling-wheel at each operation.

15 In the diagram, the sets of local out-door public fire-alarm apparatus are connected to the first and third telephone-subscribers' circuits, the sets of local out-door police signaling-apparatus are connected to the second and fourth telephone-subscribers' circuits, and the signaling wheel for the in-door automatic or manual alarm apparatus is connected through the fifth telephone-circuit. Additional sets of local police, fire, and other alarm-apparatus are connected to additional telephone-circuits as may be required. The sets of local out-door fire-alarm apparatus and the sets of local police-signaling apparatus may be entirely distinct, and the sets located wherever they will be most convenient. But wherever it is desirable to have them near each other, they may be conveniently housed in the same box or casing, as shown in the sets of fire alarm apparatus connected to the first telephone circuit and the set of police-signaling apparatus connected to the second telephone-circuit. When this is done, one telephone-set 30^a will serve for both, a switch 31 being provided to shift the telephone connection to either class of service.

40 But one of the local stations of the in-door automatic service is indicated in the diagram. Two signaling wheels 10^c and 10^e are shown, and are operated by the same mechanism, which may be such as is shown in connection with the municipal fire-alarm service. One of the wheels connects one of the leads of the telephone circuit to ground, and the other connects the other lead to ground. It is only necessary that the lead which is connected to the same common-battery at the exchange should be grounded, and the object of the other wheel is to guard against the local-alarm set being rendered inoperative by a transposition of the telephone-wires at any point between the point of connection of the local set and the exchange battery. The wheels are preferably arranged so that both leads will be connected to ground at the same moment.

45 The signals from the in-door automatic service are received at the exchange in the circuit 14^e and repeated by a relay 18^e to the private alarm-receiving headquarters.

50 A register 32 is also connected with this relay, so that the signals will be recorded at the exchange. A second relay 33 is also placed in the circuit 14^e, and controls a contact in the municipal fire-alarm circuit. But this contact is normally short-circuited by an automatic switch 34, so that the first automatic alarm-signal will not be repeated onto the municipal alarm-circuit, for such first signals are usually local trouble or test signals, and their indication at the fire-headquarters would be objectionable to the fire departments. The automatic switch is in the form of a contact-wheel, and is connected to a gear-train, which is released for a limited time by a magnet 35 in the circuit 14^e. This mechanism, whenever started, leaves the switch closed for a time corresponding to the time taken by the signal-wheels for their first revolution, and then opens the switch, so that all following signals of the same alarm will pass to the municipal fire headquarters. When the mechanism stops, it again closes the switch, so that subsequent trouble or test signals on any of the circuits of this class will be cut out from the municipal fire-headquarters.

55 What I claim and desire to secure by Letters Patent of the United States is:

1. The combination of a telephone-apparatus, a telephone-exchange, a telephone-circuit connecting the telephone-apparatus with the telephone-exchange and grounded at the exchange, a local alarm-transmitting apparatus for effecting grounded connections with one of the leads of the telephone-circuit, a battery in the circuit which is established by the local-alarm-transmitting apparatus through the ground at the exchange, a neutral relay in the leads of the telephone-circuit, the relay being at the exchange and responsive to currents controlled by the local alarm-transmitting apparatus and not to the telephone-signaling and talking currents, and an alarm-receiving apparatus which is independent of the telephone-circuit and is controlled by the relay, substantially as described.

60 2. The combination of a telephone-apparatus, a telephone-exchange, a telephone-circuit connecting the telephone-apparatus with the telephone-exchange and having one of the leads grounded at the exchange, a local alarm-transmitting apparatus for establishing grounded connections with the telephone-circuit, a battery in the circuit which is established by the local alarm-transmitting apparatus through the ground at the exchange, a neutral relay in the leads of the telephone-circuit, the relay being at the exchange and responsive to currents controlled by the local alarm-transmitting apparatus and not to the telephone-signaling and talking currents, and an alarm-receiving appa-

ratus which is independent of the telephone-circuit and is controlled by the relay, substantially as described.

3. The combination of a telephone-apparatus, a telephone-exchange, a grounded common-battery therefor, a telephone-circuit connecting the telephone-apparatus with the telephone-exchange and having one of the leads connected with the common-battery and 5 the other lead grounded at the exchange, a local alarm-transmitting apparatus for establishing grounded connections with the lead which is connected to the common-battery, a neutral relay in the leads of the telephone-circuit, the relay being at the exchange and responsive to currents controlled by the local alarm-transmitting apparatus and not to the telephone-signaling and talking currents, and an alarm-receiving apparatus which is independent of the telephone-circuit and is controlled by the relay, substantially as described.

4. The combination of sets of telephone-apparatus, a telephone-exchange, telephone-circuits connecting the sets of telephone-apparatus with the telephone-exchange and grounded at the exchange, a local alarm-transmitting apparatus for establishing grounded connections with one of the leads 10 of each telephone-circuit, a battery for supplying the circuits which are established through the ground at the exchange, a neutral relay in each pair of leads of each telephone-circuit, the relays being at the exchange and responsive to currents controlled by the sets of local alarm-transmitting apparatus and not to the telephone-signaling and talking currents, an alarm-transmitting circuit at the exchange which is controlled 15 by any of the relays, and an alarm-receiving apparatus which is operated from the alarm-transmitting circuits, substantially as described.

5. The combination of sets of telephone-apparatus, a telephone-exchange, telephone-circuits connecting the sets of telephone-apparatus with the telephone-exchange and having one of the leads of each telephone-circuit grounded at the exchange, a local alarm-transmitting apparatus for establishing 20 grounded connections with each telephone-circuit, a battery for supplying the circuits which are established by the sets of local alarm-transmitting apparatus through the ground at the exchange, a neutral relay in each pair of leads of each telephone-circuit, the relays being at the exchange and responsive to currents controlled by the sets of local alarm-transmitting apparatus and 25 not to the telephone-signaling and talking currents, an alarm-transmitting circuit at the exchange which is controlled by any of the relays, and an alarm-receiving apparatus which is operated from the alarm-transmitting circuit, substantially as described.

6. The combination of sets of telephone-apparatus, a telephone-exchange, a grounded common-battery therefor, telephone-circuits connecting the sets of telephone-apparatus with the telephone-exchange, one of the leads 30 of each circuit being connected to the common-battery and the other being grounded at the exchange, a local-alarm transmitting apparatus for establishing grounded connections with the lead of each telephone-circuit which is connected to the common-battery, a neutral relay in each pair of leads of each telephone-circuit, the relays being at the exchange and responsive to currents controlled by the sets of local alarm-transmitting apparatus and not to the telephone-signaling and talking currents, an alarm-transmitting circuit at the exchange, which is controlled by any of the relays, and an alarm-receiving apparatus which is operated from the alarm-transmitting circuit, substantially as described.

7. The combination of sets of telephone-apparatus, a telephone exchange, telephone-circuits connecting the sets of telephone-apparatus with the telephone-exchange, a local alarm-transmitting apparatus connected to one of the leads of each telephone circuit, a relay in each telephone circuit, the relays being at the exchange and responsive to currents controlled by the sets of local alarm-transmitting apparatus and not to the telephone-signaling and talking currents, an alarm-transmitting circuit at the exchange which is controlled by any of the relays, a slow-acting cut-out switch magnet operating in conjunction with each relay to cut off the control of the alarm-transmitting circuit by the relay, and an alarm-receiving apparatus which is operated from the alarm-transmitting circuit, substantially as described.

8. The combination of sets of telephone-subscribers' apparatus, a telephone-exchange, telephone-circuits connecting the sets of telephone-subscribers' apparatus with the telephone-exchange, a local alarm-transmitting apparatus for sending alarms by establishing grounded connections with one of the leads in each telephone-subscriber's circuit, a battery for supplying the circuits which are 110 established through the ground at the exchange, a neutral relay in each pair of leads of each telephone-circuit, the relays being at the exchange and responsive to currents controlled by the sets of local alarm-transmitting apparatus and not to the telephone-subscribers' signaling and talking currents, an alarm-transmitting circuit at the exchange which is controlled by any of the relays, a local alarm-receiving apparatus in conjunction with each local alarm-transmitting apparatus, and means for operating each local alarm-receiving apparatus from any of the sets of local alarm-transmitting apparatus, substantially as described.

9. The combination of sets of telephone-subscribers' apparatus, a telephone-exchange, telephone-circuits connecting the sets of telephone-subscribers' apparatus with the telephone-exchange, a local alarm-transmitting apparatus for sending alarms by establishing grounded connections with one of the leads in each telephone-circuit, a battery for supplying the circuits which are established through the ground at the exchange, a neutral relay in each pair of leads of each telephone-circuit, the relays being at the exchange and responsive to currents controlled by the sets of local alarm-transmitting apparatus, and not to the telephone-subscribers' signaling and talking currents, an alarm-transmitting circuit at the exchange which is controlled by any of the relays, a local alarm-receiving apparatus in conjunction with each local alarm-transmitting apparatus, the sets of local alarm-receiving apparatus being connected to the leads of the telephone-subscribers' circuits in circuits which are independent of the circuits through the sets of local alarm-transmitting apparatus, and means for operating each local-alarm-receiving apparatus from any of the sets of local-alarm-transmitting apparatus, substantially as described.
10. The combination of a telephone-apparatus, a telephone-exchange, a grounded common-battery therefor, a telephone-circuit connecting the telephone-apparatus with the telephone-exchange and having one of the leads connected to the common-battery and the other lead grounded at the exchange, a local alarm-transmitting apparatus for establishing grounded connections to both leads of the telephone-circuit, a neutral relay in the leads of the telephone-circuit, the relay being at the exchange and responsive to currents controlled by the local alarm-transmitting apparatus and not to the telephone-signaling and talking currents, and an alarm-receiving apparatus which is independent of the telephone-circuit and is controlled by the relay, substantially as described.
11. A combined telephone and alarm system comprising the combination of a telephone instrument, an alarm instrument, a telephone exchange, a common circuit connecting the telephone and alarm instruments with the exchange, a source of operating current therefor at the exchange, an independent electrical connection from the alarm instrument to the source of current at said exchange, an alarm receiving apparatus with connections, and automatic means connected with said common circuit at said exchange permitting signal and talking currents to pass between said exchange and said telephone instrument without affecting said alarm-receiving apparatus but causing signals from said alarm instrument to be transmitted to said alarm receiving apparatus.
12. A combined telephone and alarm system comprising, a telephone instrument, an alarm signaling instrument, a telephone exchange, a common circuit having two leads connecting the telephone and alarm instruments with the exchange, a common battery for said circuit and at said exchange, an independent circuit connecting said alarm instrument and said exchange and connections for establishing a circuit between said independent circuit and both leads of said common circuit between said telephone instrument and said exchange.
13. A combined telephone alarm system comprising the combination of the telephone exchange, line wires leading therefrom, an alarm receiving instrument with leads connected to said exchange, a telephone instrument connected to said line wires, alarm signaling apparatus connected to said line, a telephone instrument connected with said alarm signal instrument, a telephone instrument connected to said alarm receiving instrument leads and means for preventing the ordinary telephone and signaling currents from being transmitted to said alarm receiving instrument but permitting the alarm signals to be transmitted.
14. A combined telephone and alarm system comprising a telephone exchange, line wires leading therefrom, a telephone instrument connected to said wires for talking through said exchange, alarm signaling apparatus having a grounded connection with said exchange and connected to send an alarm through a circuit including one of said line wires and said grounded connection, alarm receiving apparatus connected to said exchange, a coil winding connected in each of said line wires, and means cooperating therewith for automatically transmitting alarm signals between said signaling and receiving apparatus, but permitting ordinary signaling and talking currents to pass between said exchange and said telephone instrument.
15. A combined telephone and alarm system comprising the combination of a telephone exchange, a telephone instrument with a complete circuit to said exchange, alarm signaling apparatus connected to said circuit, alarm receiving apparatus, a coil winding in each branch of said circuit, so arranged as to permit the ordinary signaling and talking currents to be transmitted through said circuit, and means for causing alarms from said signaling apparatus to be automatically transmitted to said receiving apparatus.
16. A combined telephone and alarm system including a telephone exchange, a telephone instrument, a complete circuit be-

- tween said instrument and said exchange for transmitting signaling and talking currents, alarm signaling apparatus connected to said circuit, alarm receiving apparatus connected to said exchange, a telephone instrument connected with said alarm signaling apparatus, a telephonic instrument connected with said alarm receiving apparatus, means for permitting ordinary talking and signaling currents to be transmitted through said circuit, and means for automatically transmitting alarms from said signaling apparatus to said receiving apparatus, and permitting telephonic communication between such apparatus. 15
17. A combined telephone and alarm system, comprising the combination of a plurality of telephone instruments and alarm instruments associated with each telephone instrument, a telephone exchange, a common circuit connecting each telephone and its corresponding alarm instrument with the exchange, a common source of operating current for all of said alarm instruments, an independent electrical connection from each alarm instrument to the source of current, alarm receiving apparatus, and means connected with each common circuit for permitting signal and talking currents to pass between the exchange and the telephone instruments without affecting the alarm receiving apparatus, but causing signals from the alarm instruments to be transmitted to the alarm receiving apparatus. 25
18. A combined telephone and alarm system, comprising a plurality of telephone instruments and alarm signaling instruments associated with each telephone instrument, a telephone exchange, a circuit having two leads connecting each telephone instrument with the exchange, a common source of operating current for all of said alarm instruments, an independent electric circuit connecting each alarm instrument, and a source of current and means for establishing electrical connection between said independent circuit and both leads of the corresponding telephone circuit. 35
19. A combined telephone and alarm system comprising a telephone exchange, line wires leading therefrom, an alarm receiving instrument, a plurality of telephone instruments connected to said line wires, alarm signaling apparatus associated with each telephone instrument, an individual telephone instrument connected with each alarm signaling apparatus, a telephone instrument connected to the alarm receiving instrument, and means for preventing the ordinary telephone and signaling currents between the subscriber's instrument and the exchange from being transmitted to the alarm receiving instrument, but permitting alarm signals to be transmitted between the alarm signal- 40
- ing apparatus and the alarm receiving instrument. 45
20. A combined telephone and auxiliary signaling system, comprising a telephone exchange, a series of telephone instruments, circuits connecting said instruments with said exchange, an auxiliary electrical instrument connected to each circuit adjacent its telephone instrument, a common complementary auxiliary electrical instrument, an independent electrical connection between the individual auxiliary instrument and the common auxiliary instrument, a source of operating current for said auxiliary instruments, and means for permitting ordinary talking and signaling currents to pass between the telephone instruments and the exchange without affecting the auxiliary instruments, but permitting signals to be transmitted between the auxiliary instruments. 50
21. A combined telephone and auxiliary signal and recording system, comprising a telephone exchange, a plurality of subscribers' telephone instruments, circuits connecting the telephone instruments with the exchange, an auxiliary electrical instrument connected with each telephone instrument circuit, centrally located complementary auxiliary electrical apparatus with means for receiving and recording signals at said exchange, a source of operating current at said exchange for said auxiliary apparatus, and an independent electrical connection between each individual auxiliary instrument and the centrally located auxiliary apparatus. 55
22. A combined telephone and alarm system, comprising the combination of a telephone instrument, an alarm instrument, a telephone exchange, a common circuit connecting the telephone and alarm instruments with the exchange, a common source of operating current for said telephone and alarm instruments, an independent electrical connection from the alarm instrument to the exchange, alarm receiving apparatus, and means associated with said common circuit responsive to the telephone signal and talking currents and causing signals from said alarm instruments to be transmitted to said alarm receiving apparatus. 60
23. A combined telephone and alarm system, comprising the combination of a plurality of telephone lines leading from subscribers' stations to a central station, telephone sets at the subscribers' stations and telephonic apparatus at the central station coöperative therewith for conversational purposes, a plurality of auxiliary signaling instruments grounded at outlying points and adapted to transmit distinctive signaling currents over the telephone lines, alarm registering apparatus at the central station hav- 65

- ing mechanism responsive to distinctive signaling currents from the auxiliary instruments but unresponsive to the telephone signaling and talking currents, alarm receiving 5 apparatus outside the central station, and means for automatically transmitting the distinctive signals through the alarm registering apparatus within the central station to the alarm receiving apparatus.
- 10 24. A combined telephone and alarm system, comprising a telephone exchange, a telephone instrument, a circuit connecting said instrument with said exchange, an alarm instrument connected to said telephone circuit, an alarm receiving and recording device at said exchange, electromagnetic means unresponsive to the ordinary talking and signaling currents for automatically transmitting distinctive signaling 15 currents to said receiving and recording device, private headquarters receiving apparatus, and means controlled by said exchange alarm receiving and recording device for automatically transmitting the distinctive signals to said private headquarters receiving apparatus.
- 20 25. A combined telephone and alarm system, comprising the combination of a telephone exchange, a telephone instrument, a circuit connecting said instrument with said exchange, distinctive signaling apparatus connected to said circuit, alarm receiving and registering apparatus at the exchange, electro-responsive apparatus having a coil 25 winding in each branch of said circuit unresponsive to the ordinary talking and signaling currents but responsive to distinctive signaling currents for transmitting said distinctive signaling currents to said alarm receiving and registering apparatus.
- 30 26. A combined telephone and alarm system, comprising a telephone exchange, a plurality of telephone instruments, circuits connecting said instruments with said exchange, distinctive signaling apparatus connected to a plurality of said circuits, alarm receiving and registering apparatus at said exchange, and electro-responsive mechanism including a coil winding in each branch of 35 each circuit unresponsive to the ordinary talking and signaling currents but responsive to distinctive signaling currents for transmitting the distinctive signals to said receiving and registering apparatus.
- 40 27. In a telephone exchange, the combination with a plurality of telephone lines leading from the subscribers' stations to the central station, of telephone sets at the sub-stations and telephonic apparatus at the central station to coöperate with said lines for conversational purposes, alarm transmitting apparatus at outlying points adapted to transmit distinctive signaling currents over the telephone lines, alarm receiving and registering apparatus at the central station, and electro-responsive mechanism individual to each line including coil windings in each branch of each line responsive to said distinctive signaling currents but unresponsive to the telephone signaling and talking currents. 70
- 45 28. In a telephone exchange, the combination of a telephone line leading from the subscriber's station to the central station, and a telephone set at the sub-station and telephonic apparatus at the central station to coöperate with said line for conversational purposes, distinctive signaling apparatus at an outlying point connected to said line, alarm receiving and registering apparatus at the central station, and electro-responsive mechanism including coil windings in each branch of the line responsive to the distinctive signaling currents but unresponsive to the telephone signaling and talking currents. 75
- 50 29. The combination of a subscriber's telephone and exchange, a circuit connecting said subscriber's telephone and exchange having an outgoing and an incoming lead, said circuit being grounded at the subscriber's station and at the exchange and additional telephone receiving and transmitting apparatus connected to the ground and inductively connected to both leads so as to transmit signals through the circuit made up of the ground connections in series and 80 said two leads in parallel, a signaling transmitting apparatus electrically connected directly to one of said leads and a receiving relay connected to said lead at the exchange and in series with said signaling transmitting apparatus. 85
- 55 Signed by me in Philadelphia this 13th day of April, 1900.
